(57) **CLAIM**

We claim the ornamental design for a wear cap for excavator bucket, as shown and described.

DESCRIPTION

FIG. 1 is a top perspective view of a wear cap for excavator bucket, showing our new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a bottom perspective view thereof; and,

FIG. 9 is a reference view thereof showing an example configuration of use in which the wear cap for excavator bucket may be applied to a tooth adapter that is fitted into a tooth part of an excavator bucket body.

The dash-dash broken lines in the drawings show portions of the wear cap for excavator bucket that form no part of the claimed design. The dot-dash broken lines in the drawings depict boundaries of the claim and form no part thereof.
